PAINT ROLLER TRAY LINER

Ted L. Paxton, P.O. Box 2006,
Riverside, Calif. 92506

Filed Nov. 7, 1966, Ser. No. 4,575

Term of patent 14 years

(Cl. D9—2)

FIG. 2.

FIG. 1 is a perspective view of a paint roller tray liner looking at same from above showing my new design.

FIG. 2 is a top plan view thereof.

The opposite side to that shown has substantially the same appearance as the side shown. The rear is flat and plain, except as indicated.

I claim:

The ornamental design for a paint roller tray liner, as shown and described.
